UNITED STATES PATENT OFFICE.

VICTOR H. SLINACK, OF PHILADELPHIA, PENNSYLVANIA, ASSIGNOR TO PENNSYLVANIA GLOBE GAS LIGHT COMPANY, OF PHILADELPHIA, PENNSYLVANIA, A CORPORATION OF PENNSYLVANIA.

INVERTED INCANDESCENT GAS-BURNER.

1,072,781.

Specification of Letters Patent. Patented Sept. 9, 1913.

Application filed June 19, 1912. Serial No. 704,482.

To all whom it may concern:

Be it known that I, VICTOR H. SLINACK, a citizen of the United States, residing at the city of Philadelphia, in the county of Philadelphia and State of Pennsylvania, have invented a certain new and useful Inverted Incandescent Gas-Burner, of which the following is a specification.

The principal object of the present invention is to provide for keeping all the mantles or incandescents of the group of mantles or incandescents of a burner equally bright, or in other words to keep all the mantles of the burner of uniform brightness.

Another object of the invention is to provide a comparatively inexpensive, reliable and simple inverted incandescent gas burner of high candle power.

Other objects of the invention will appear from the following description.

The invention will be claimed at the end hereof, but will be first described in connection with the embodiment of it chosen for illustration in the accompanying drawings, in which—

Figure 1, is a side view partly in section. Fig. 2, is a sectional plan view on the line 2—2 of Fig. 1. Fig. 3, is a sectional view on the line 3—3 of Fig. 1, looking upward.

In the drawings the incandescent gas burners 1 having burner tubes 2 constitute a group of, as shown in the drawings, five burners, but the number may be increased or diminished. It will usually be three or more, but the number is not to be regarded as essential.

3, is a tubular gas supply ring shown as arranged concentric with the group of incandescent gas burners.

4, is a tubular gas supply yoke from the arms 5 of which the ring 3 is suspended.

6, are inverted U-shaped Bunsen tubes each provided with a gas controller 7 and rising from the ring 3. These Bunsen tubes make up a group containing, as shown in the drawings, three Bunsen tubes spaced around the ring 3, although the number of Bunsen tubes may be increased or diminished.

8, is a mixing and supply chamber common to all the Bunsen tubes and to all the burner tubes and having a convex mixing surface 9. This surface 9 is shown as of the

form of a part of a sphere and the Bunsen tubes are shown as discharging into the top of the chamber 8 and the burner tubes are shown to lead radially or thereabout from the base of the mixing chamber.

10, is an ignition gas flooding tube which by-passes the Bunsen tubes and communicates with the burner tubes by way of the chamber 8.

11, is an inner shell mounted on the side wall of the mixing chamber 8 and inclosing the descending parts of the Bunsen tubes 6.

12, is an outer shell excluding the rising parts of the Bunsen tubes and the arms 5 of the yoke. As shown the plate 13^a incloses the bottom of the mixing chamber and constitutes in effect a part of the inner shell, and is supported by a screw 13 connected with the base of the chamber 8, and the outer shell is supported by screws 14 that are connected with the ends of the arms 5 of the yoke.

15, is a deflector which, if desired, may also be a reflector and it extends outwardly from the base of the outer shell.

The products of combustion pass up between the outer and inner shells and therefore are not taken in at the air inlets 16 of the Bunsen tubes. These shells protect the supply connections of the burner from undue exposure to the heat of the products of combustion. In the chamber 8 a thorough stirring up of the mixture of gas and air is effected and the surface 9 promotes such thorough stirring up as does also the described arrangement of the inlet and outlet tubes in respect to that chamber. Even though the mixture of air and gas in each individual Bunsen tube may not be the same, still the passage of these mixtures from the various Bunsen tubes through and their stirring up in the chamber 8 result in a uniform supply of the same kind of mixture to each of the burners so that they are all equally or uniformly bright, which is obviously important, as a group of mantles of unequal brilliancy in a burner presents an unsightly appearance.

100 The function of the ignition gas flooding tube 10 is to purge the apparatus of air and supply pure gas at the mantles when the burner is lighted, thus avoiding explosions

at that time and it is well understood that when the burner is burning the supply of gas through the tube 10 is cut off.

What I claim is:

- 5 1. An inverted incandescent gas burner comprising the combination of a group of incandescent gas burners having burner tubes, a gas supply ring, a gas supply yoke from the arms of which the ring is suspended, a group of inverted U-shaped Bunsen tubes rising from the ring, and a mixing and supply chamber common to all the Bunsen tubes and to all the burner tubes, substantially as described.
- 10 2. An inverted incandescent gas burner comprising the combination of a group of incandescent gas burners having burner tubes, a gas supply ring, a gas supply yoke from the arms of which the ring is suspended, a group of inverted U-shaped Bunsen tubes rising from the ring, a mixing and supply chamber common to all the Bunsen tubes and to all the burner tubes, and an ignition gas flooding tube by-passing the Bunsen tubes and communicating with the mixing and supply chamber, substantially as described.
- 15 3. An inverted incandescent gas burner comprising the combination of a group of incandescent gas burners having burner tubes, a gas supply ring, a gas supply yoke from the arms of which the ring is suspended, a group of inverted U-shaped Bunsen tubes rising from the ring, a mixing and supply chamber common to all the Bunsen tubes and to all the burner tubes, an inner shell inclosing the bottom and side walls of the mixing chamber and the descending

parts of the Bunsen tubes, and an outer shell excluding the rising parts of the Bunsen tubes and the arms of the yoke, substantially as described.

4. An inverted incandescent gas burner comprising the combination of a group of incandescent gas burners having burner tubes, a gas supply ring, a gas supply yoke from the arms of which the ring is suspended, a group of inverted U-shaped Bunsen tubes rising from the ring, a mixing and supply chamber common to all the Bunsen tubes and to all the burner tubes, an inner shell inclosing the bottom and side walls of the mixing chamber and the descending parts of the Bunsen tubes, an outer shell excluding the rising parts of the Bunsen tubes and the arms of the yoke, and a deflector extending outwardly from the base of the outer shell, substantially as described.

5. An inverted incandescent gas burner comprising the combination of a gas supply yoke, a gas supply ring carried by the arms of the yoke, inverted U-shaped Bunsen tubes rising from the ring and depending inward toward the center thereof, a mixing and supply chamber depending from the descending ends of the Bunsen tubes, and burner tubes communicating with the base of the chamber and carried thereby, substantially as described.

In testimony whereof I have hereunto signed my name.

VICTOR H. SLINACK.
